UNITED STATES PATENT OFFICE

PAUL F. YUNGLING, OF LOS ANGELES, CALIFORNIA, ASSIGNOR TO SCOTT-ROSS AND COMPANY, OF LOS ANGELES, CALIFORNIA, A CORPORATION OF DELAWARE

FLUID-OPERATED PUMP

Application filed March 20, 1928. Serial No. 263,105.

This invention relates to fluid-operated pumps of the type employed, for example, in oil wells and an important object is to improve the operation of this type of pump. 5 Another object is to provide a construction that will dispose of the gas in such a way as to not interfere with the operation of the pump plunger and the pump valves.

Another object is to prevent any foreign 10 objects, that may be entrained by the power fluid, from passing through the valve mechanism and into the working barrel.

Another object is to prevent scoring of the 15 pump plunger and working barrel by sand and other small particles of the formation in which the pump is working.

Another object is ease of installing and removing the pump.

Other objects and advantages will appear 20 in the subjoined detailed description.

The accompanying drawings illustrate the invention:

Figures 1 to 5 inclusive are vertical sections of a construction embodying my new 25 fluid-operated pump, portions being broken away to contract some of the views. The views taken in numerical order represent successive portions of the pump beginning at the upper end thereof.

30 Figures 6, 7 and 8 are enlarged horizontal sections on the lines indicated by 6—6, 7—7, 8—8, respectively, Figures 1, 3 and 4, respectively.

Figure 9 is a reduced, fragmental, vertical 35 section on the line indicated by 9—9, Figure 8.

Figure 10 is a horizontal section of the lower housing head on the line indicated by 10—10, Figure 3.

Figure 11 is a broken longitudinal reduced 40 view of the fluid-operated pump shown in Figures 1 to 5.

Figure 12 is an enlarged longitudinal view, partly in section, of the valve mechanism.

Figure 13 is a view of the opposite side of 45 the valve mechanism from that illustrated in Figure 12.

Figures 14, 15 and 16 are enlarged horizontal sections on the lines indicated by 14—14, 15—15, 16—16, respectively, Figure 13.

50 Figure 17 is an enlarged inverted plan view

from the line indicated by 17—17, Figure 13.

The well casing is indicated at 11 and is provided at its upper end with a casing head 12 in the customary manner. Extending downwardly through the casing 11 is a string 55 of pump tubing 13 to the lower end of which is connected by a reducing coupling 14, a discharge head 15. To the lower end of the head 15 is connected by a coupling 16 a working barrel comprising an outer barrel body 17 and a liner 18. Screw threaded onto the lower end of the working barrel is a standing valve seat 19 in which is removably seated a standing valve 20.

Working in the working barrel is a tubular 65 valved plunger 21, the valve being indicated at 22 at the upper end of the plunger.

Above the head 15 is a connecting rod guide comprising an outer jacket 23, intermediate liner 24 and an inner liner 25. The liner 25 70 is shorter than the liner 24 so that the guide bore portion 26 is of larger cross sectional area than the guide bore portion 27. The jacket 23 is screwed at its lower end into the upper end of the head 15. Working in the 75 guide is a stepped connecting rod comprising a section 28 that works in the larger bore portion 26 and a section 29 that works in the smaller bore portion 27. The sections 28, 29 are connected together for simultaneous 80 movement and, in this instance, the connection is effected by screwing the sections together as indicated at 30. The lower end of the rod section 28 connects with the plunger valve 22 so that reciprocation of the connecting rod will effect reciprocation of the plunger 21. The liners 24, 25, closely fit the connecting rod so that leakage past said rod will be minimized.

The coupling 14 is provided with an internal, beveled seat 31 in which seats an external, beveled portion 32 on the head 15. Thus, when the tubing 74 is pulled, the head 15 will become detached from the seat 31 and, accordingly, those parts that hang suspended 90 from the seat 31 will be withdrawn through said seat. There is a great advantage in providing the seat 31 at this level because the pump working barrel lies below this level 95 and is in tension and is not in compression as 100.

it would be if the pump barrel were supported from below. If the support were from below the working barrel would be thrown out of alignment and thus interfere with accurate working of the plunger in the barrel and also induce unevenness of wear on the plunger and working barrel.

The connecting rod passes through the bore 33 of the head 15 and is of materially less diameter than said bore so that the fluid being pumped can pass the connecting rod on its way to the chamber 34, with which the head is provided. It is to be particularly noted that the cross sectional area of the portion of 15 the connecting rod that, on its down stroke, enters the working barrel is less than the cross sectional area of the plunger. This results in the connecting rod displacing fluid in the working barrel on the down stroke of the 20 plunger. The fluid discharges from the head 15 through a port or ports 35 formed in said head, said ports 35 opening through the upper end of the gas trap and communicating with the interior of the tubing 13. The ports 25 35 are controlled by downwardly closing check valves 36 which open to allow the fluid to discharge.

The upper end of the jacket 23 connects with a cylinder 37, said upper end, in this 30 instance, being screwed into a reducing coupling 38 that is screwed into the lower end of the cylinder 37. The coupling 38 constitutes the lower head of the cylinder 37. Working in the cylinder 37 is a piston 39, 35 which is closed at its opposite ends, the lower end of said piston having a screw threaded connection with the connecting rod section 29. The upper head of the cylinder is indicated at 40 and is provided with a longitudinally extending duct 41 that communicates at its lower end with the bore of the cylinder and at its upper end with a chamber 42 in the head 40. Above the chamber 42 is a port 43 in the lower head 44 of a housing 45, the 40 lower end of said port being provided with a valve seat 46 on which closes a downwardly opening valve 47. The port 43 extends upwardly, thence outwardly to the periphery of the head 44 so as to communicate with 45 the space between the housing 45 and the tubing 13. The head 44 is provided with another port 48 controlled by a downwardly opening valve 49. The port 48 opens laterally to the periphery of the head 44 so as to communicate at its upper end with the space between the housing 45 and tubing 13. The lower end of the port 48 communicates with a chamber 50 in the head 44. The upper end of the housing 45 is provided with a head 51 50 and with ports 52, 53 in said head. The ports 52, 53 are controlled by upwardly opening valves 54, 55, respectively, and when said valves are open, said ports communicate with a chamber 56. The lower end of the 55 port 52 communicates with a conduit

which extends downwardly alongside of the housing 45 and which communicates at 58 with the chamber 50 and, also, extends downwardly alongside of the cylinder 37 and communicates at 59 with the lower end portion of 70 the cylinder bore. The lower end of the port 53 communicates with a conduit 60 that extends downwardly alongside of the housing 45 and communicates at its lower end at 61 with the chamber 42.

The valves 47, 49, 54 and 55 constitute portions of a fluid-operated valve mechanism which is housed by the housing 45. Any suitable fluid-operated valve mechanism may be employed for controlling the opening and closing of the valve 47, 49, 54 and 55, and at present I prefer to employ the valve mechanism disclosed in my co-pending application, Serial No. 226,412, filed October 15, 1927.

The valve mechanism hereinbefore referred to is constructed as follows: There is provided a body 111 which, in this instance, is practically cylindrical and is chambered as indicated at 112. The body 111 includes cover plates 113 which fit in openings 114 at opposite sides of the chamber 112, said openings communicating with said chamber. The cover plates 113 are secured in place by cap screws 115.

Reciprocatably mounted in the body 111 is a rod 116, said rod, in this instance, being positioned axially of the chamber 112. The rod 116 is provided with a number of cams, an upper cam 117 and a lower cam 118. The cam 117 is provided with an upwardly and inwardly tapered cam face 119 and with a downwardly and inwardly tapered cam face 120, and the lower cam 118 is provided with an upwardly and inwardly tapered cam face 121 and a downwardly and inwardly tapered cam face 122.

The cam 117 operates a rocker arm 123 and the cam 118 operates rocker arms 124, 125, and 126. The rocker arms 123, 126 are pivoted at 127 in one of the cover plates 113, and the rocker arms 124, 125 are pivoted at 128 in the other cover plate 113.

The free end of the rocker arm 126 is adapted to operate the valve stem 129 of the valve 55. The free end of the rocker arm 125 is adapted to operate the valve stem 131 of the valve 54. The free end of the rocker arm 124 is adapted to operate the valve stem 133 of the valve 49, and the free end of the rocker arm 123 is adapted to operate the valve stem 135 of the valve 47.

Between the upper end of the valve stem 135 and the free end of the rocker arm 123 is interposed a push rod 137 that is slidably mounted in bearings 138 secured to one of the plates 113. Interposed between the upper end of the valve stem 133 and the free end of the rocker arm 124 is a push rod 139 which is slidably mounted in bearings 140 secured to 130

one of the cover plates 113. Between the lower end of the valve stem 131 and the free end of the rocker arm 125 is interposed a push rod 141 which is slidably mounted in bearings 142 projecting from one of the cover plates 113. Interposed between the lower end of the valve stem 129 and the free end of the rocker arm 26 is a push rod 143 that is slidably mounted in bearings 144 secured to one 10 of the cover plates 113.

The valve 55 controls the port 53 extending downwardly from the upper end of the body 111, thence laterally to the periphery of said body. The valve 54 controls the port 52 15 that extends downwardly from the upper end of the body 111, thence laterally to the periphery of said body. The valve 49 controls the port 48 that extends upwardly from the lower end of the body 111, thence outwardly to the 20 periphery of said body. The valve 47 controls the port 43 that extends upwardly from the lower end of the body 111, thence laterally to the periphery of said body.

The port 53 communicates with a conduit 25 491 which, in this instance, is formed in part by a pipe and in part by a duct 491 which extends laterally from the periphery of the body 111, thence to the lower end of said body. The ports 48, 52 are connected by a conduit 30 150 which, also, in this instance, is formed by a pipe that extends lengthwise of the body 111. The valves 47, 49, 54, 55 are yieldingly held closed and are moved into closed positions by coil springs 132 that surround the 35 valve stems between shoulders 152 on the valve stems and the adjacent end wall of the chamber 112.

In the instance illustrated in the drawings, each rocker arm at the end that engages its 40 actuating cam is provided with a roller 153 so as to minimize wear.

I provide a construction for suspending the valve mechanism and the cylinder so that the same will be in tension, thus avoiding the 45 liability to throwing of the parts of the valve mechanism and the cylinder out of alinement as would be liable to occur if said parts were supported from below. For this purpose the chamber 56, which comprises a short piece 50 of tubing 62 and a plug 63 closing the upper end of said tubing, connects with a short piece of tubing 64 which is of less diameter than the plug 63 so that said plug forms a shoulder 65 at the bottom of the tubing 64. The tubing 64 passes through the bore 66 of a support 67 and is provided with a shoulder 68 above the level of the support 67. The support 67 has vertical openings 69 extending therethrough for the passage of the fluid. When 60 the pump is in place, the shoulder 68 rests upon the upper face of the support 67. In this instance, the support 67 constitutes a reducing coupling being screw threaded into the adjacent ends of tubing sections 70, 71 65 of different diameters, said tubing sections

constituting different portions of the tubing which is indicated in general at 13.

The tubing 64 extends upwardly from the shoulder 68 and is closed at its upper end as indicated at 72. The upper end portion of the tubing 64 constitutes a screen, being provided with perforations 73 so as to permit of the entrance of an operating fluid and exclude foreign objects that may have been entrained in said operating fluid. Preferably the closed 75 end 72 is tapered, as shown, so as to form a guide for slipping thereover of the macaroni tube indicated at 74. The perforated portion of the tubing 64 is of smaller diameter than the unperforated portion 75 below the 80 perforated portion, and the inside diameter of the macaroni tubing is sufficiently great to form a space between the perforated portion and the macaroni tubing so that the power fluid can flow down around the perforated portion and through the perforations into the tubing 64. The lower portion of the macaroni tubing constitutes a sleeve that closely fits the tube portion 75, said sleeve comprising an outer jacket 76 and a liner 77. 85 The sleeve also comprises a cap 78 that is screwed onto the lower end of the jacket 76. The sliding fit between the sleeve 76, 77 and the tubing portion 75 prevents the power fluid from leaking past the tubing portion 75. The 90 upper end of the jacket 76 is screwed into a reducing coupling 91 which is provided with an internal tapered seat 92 to receive the externally tapered portion 93 of a reducing coupling 94 that is screwed into the tubing section 100 75. Into the coupling 94 is screwed a handling nipple 95 which connects the coupling with the screen 96. The coupling 91 connects the jacket 76 with the macaroni section 95 97 that is of smaller diameter than said 105 jacket.

The cylinder 37, housing 45 and the conduits 57, 60 are enclosed in a jacket 99 formed by an enlarged portion of the pump tubing 13, said jacket being connected at its upper 110 end by a reducing coupling 98 with that portion of the pump tubing that is of smaller diameter than the jacket 99.

The valve-operating mechanism is connected for operation by suitable means with the piston 39 and these means, though they may be of any suitable construction, in this instance, are as follows: Passing through the heads 40, 44 and slidably engaging the piston 39 is a rod 79 which has on it two shoulders, an upper shoulder 80 and a lower shoulder 81. The rod 79 passes through a bore 82 in the upper piston head 83. Thus, there is provided a lost motion connection between the valve-operating mechanism and the piston for, on the upstroke of the piston, the shoulder 80 is engaged by the piston head 83 and, on the down stroke of the piston, the shoulder 81 is engaged by the piston head 83. In this instance, the shoulders 80, 81 are 120 125

formed by the lower and upper ends, respectively, of coil springs which surround the rod 79, the lower spring 81 seating against an abutment 84 on the lower end of the rod 79 and the upper spring 80 seating against an abutment 85 near the upper end of said rod. This particular type of lost motion connection is for the purpose of storing power in the springs 80, 81, which power is utilized in 10 operating the valve mechanism. It suffices to state that the valve mechanism operates to simultaneously move the valves 47, 54 into the closed positions and the valves 49, 55 into the open positions and, also to simultaneously 15 move the first mentioned valves into the open positions and the last mentioned valves into the closed positions.

The macaroni tubing 74 passes upwardly through the casing head 12 and through a 20 plug 86 that closes the upper end of the tubing 13. Near its upper end the tubing 13, above the casing head 12, is provided with a discharge pipe 87 for the fluid that is being pumped.

25 Now referring more particularly to Figs. 8 and 9 of the drawings, the smaller bore portion 26 is provided with a port 88 which communicates with a conduit 89 that extends downwardly through the discharge head 15 30 from the upper end thereof to near the lower end thereof, thence laterally to the periphery of said head 15 so as to communicate at its lower end with the interior of the casing. The purpose of this construction is to permit 35 inflow of fluid to the bore portion 26 on downward motion of the plunger rod and to permit of out-flow of said fluid from the bore portion 26 on the up-stroke of the connecting rod, thus to avoid any tendency to the formation 40 of a partial vacuum in the bore portion 26 which would consume power.

Though the plunger, piston and connecting rod may be of any suitable construction, I 45 preferably employ a special construction to eliminate or, at least, minimize scoring of the surfaces that are in sliding contact with one another and for this reason the plunger, piston and connecting rod are provided in 50 their peripheries with grooves 90. These grooves 90 are of a helical construction, thus forming screw threads that extend from end to end of the plunger, the piston and the connecting rod. When sand and other particles of the formation in which the pump is placed, 55 work between the plunger barrel and plunger, the cylinder and piston, or the connecting rod and its guide, said particles drop into the grooves 90 and, accordingly, do not act to score the surfaces that are in sliding contact.

60 The upper end of the macaroni tubing will be connected to a source of compressed fluid, which fluid furnishes the power for operating the pump and the operation is as follows: The power fluid passes down the macaroni tubing thence into the tubing 64, whence it

passes into the chamber 56. The valve 55 being open as shown in Fig. 2, the power fluid passes said valve, flows through the conduit 60 into the chamber 42, thence through the duct 41 to the upper end of the cylinder above 70 the piston 39. This forces the piston on its down stroke and the piston through the connecting rod at the same time forces the pump plunger on its down stroke. As soon as the pump plunger begins its down stroke, the 75 valve 22 opens and the standing valve 20 closes, thus causing displacement of fluid from below the pump plunger into the space above said plunger. As the connecting rod section 28 moves downwardly it displaces 80 fluid in the working barrel through the head 15 into the pump tubing. As the piston moves downwardly it displaces the fluid therebeneath within the cylinder through the conduit 57 into the chamber 50, thence 85 through the port 48 into the space between the tubing 13 and macaroni 74. When the piston almost reaches the bottom of its down stroke, it effects operation of the valve mechanism, through the rod 79 so as to close the 90 valves 49, 55 and open the valves 47, 54. As soon as this occurs, the power fluid discharges from the chamber 56 past the valve 54 into the port 52, thence through the conduit 57 into the lower end of the cylinder below the 95 piston which, accordingly, is then actuated on its up stroke. The fluid within the cylinder above the piston flows upwardly through the port 41 into the chamber 42 past the valve 47 through the port 43 and out into the space between the tubing 13 and macaroni 74. The upwardly moving piston carries with it the pump plunger and, at the beginning of the up stroke of the plunger, the valve 20 opens thus admitting fluid from the well into the 100 lower portion of the working barrel, and the valve 22 is closed by the weight of fluid above it. The ascending plunger forces the pumped fluid through the bore 33 of the head 15 into the chamber 34, thence through the ports 35 past the valves 36, thence upwardly 105 through the pump tubing 13.

The connecting rod sections 27, 28, hereinbefore described, constitute a stepped connecting rod and the advantage of the stepped construction is to cut down the volume of fluid that is pumped on the up stroke of the plunger while, at the same time, providing for a relatively great cross sectional area of the bore of the cylinder 37 and piston 39 so that the power fluid will be most effective in raising the piston. The cross sectional area of the connecting rod section 28 that enters the working barrel is preferably about one-half of that of the plunger so that the volumes of fluid discharged on the up and down strokes of the plunger will be approximately equal, thus, keeping the fluid column moving constantly and avoiding settling of the sand and other foreign solid particles that may be 110 115 120 125 130

in said fluid column. This prevents sanding up of the pump.

To pull the pump hereinbefore described, an elevator will be applied to the macaroni tubing and said tubing will be pulled out of the well, thus drawing it off the tubing 64 and uncovering the handling nipple 95. Then the casing head will be unscrewed from the collar 121 and the pump tubing will be raised until the upper end of the working barrel comes above the casing. An elevator will then be placed beneath the coupling 16 and the head 15 will be unscrewed from said coupling 16. The tubing 13 will then be raised sufficiently to pull the plunger out of the working barrel and all of the parts thus raised will then be swung to one side. Then the working barrel and the attached standing valve will be pulled out of the casing.

The last operation is to swing back over the casing the pump tubing and parts suspended thereby. The lock nut 151 which is screwed onto the head 15 beneath the coupling 14 will then be removed from said head 15 and the tubing and its suspended parts will be lowered into the casing until the elevator under the reducing coupling 98 rests on the collar 121.

An elevator will be applied to the handling nipple 95 and the tubing 64 raised sufficiently to release the shoulder 68 from the support 67. The coupling 98 will then be unscrewed from the pump jacket and the support 67 will be screwed out of the pump jacket. The tubing 64 will then be raised to lift the pump barrel off its seat 31. This permits oil to drain from the pump jacket into the casing. The elevator attached to the handling nipple 95 will then be raised sufficiently to pull the entire pump, including the valve mechanism within the housing 45 from the jacket. The parts of the pump may then be repaired or replaced, as is necessary. The jacket may remain in the well and the pump returned thereto by a reversal of the operations hereinbefore described or, if desired, said jacket may be removed from the casing.

It is to be noted that, in replacing the pump in the well, the sleeve 77 will be guided onto the tubing 64 by reason of the cap 78 engaging the cone-shaped upper end 72 of the strainer 96.

It is also to be particularly noted that before placing the pump in the well, the shoulder 68 which is screwed onto the member 64 is adjusted so that the head 15 just fits in the seat 31, the weight of the housing 45 and its contents being mainly carried by the shoulder 68, thus avoiding buckling of the housing 45 which, if it were to occur, might interfere with the operation of the valve mechanism contained within said housing 45.

I claim:

1. A fluid-operated pump comprising a vertical tube provided at its upper end with

a strainer, a power fluid induction tube slidably engaging the first mentioned tube and spaced from the strainer, pump tubing surrounding the tubes and spaced therefrom, and a means within the pump tubing operable by fluid pressure within the first mentioned tube to pump a fluid through the pump tubing.

2. A fluid-operated pump comprising a vertical tube provided at its upper end with a strainer, a power fluid induction tube slidably engaging the first mentioned tube and spaced from the strainer, pump tubing surrounding the tubes and spaced therefrom, a support connecting the first mentioned tube and the pump tubing and provided with vertical openings for the passage of a fluid, and a means connected with the first mentioned tube operable by fluid pressure therewithin to pump a fluid through the pump tubing.

3. A fluid-operated pump comprising a vertical tube provided at its upper end with a strainer, a power fluid induction tube slidably engaging the first mentioned tube and spaced from the strainer, pump tubing surrounding the tubes and spaced therefrom, a support connected with the pump tubing and provided with vertical openings for the passage of fluid, a shoulder on the first mentioned tube resting on the support, a means connected with the first mentioned tube operable by fluid pressure therewithin to pump a fluid through the pump tubing, said means including a working barrel and a member provided with an external beveled portion, and a member secured to the lower end of the pump tubing and provided with a beveled seat to receive said beveled portion.

4. A fluid-operated pump comprising a vertical tube, a power fluid induction tube slidably engaging the first mentioned tube, pump tubing surrounding the tubes and spaced therefrom, a support holding the first mentioned tube and secured to the pump tubing and provided with vertical openings for the passage of a fluid from the portion of the pump tubing above said support into the portion of said pump tubing below said support, and a means connected with the first mentioned tube operable by fluid pressure therewithin to pump a fluid through the pump tubing.

5. A fluid-operated pump comprising a vertical tube, a power fluid induction tube slidably engaging the first mentioned tube, pump tubing surrounding the tubes and spaced therefrom, a support connected with the pump tubing and provided with vertical openings for the passage of fluid, a shoulder on the first mentioned tube resting on the support, a means connected with the first mentioned tube operable by fluid pressure therewithin to pump a fluid through the pump tubing, said means including a working barrel and a member provided with an

external beveled portion, and a member secured to the lower end of the pump tubing and provided with a beveled seat to receive said beveled portion.

- 5 6. A pump comprising pump tubing, a working barrel, a valved plunger in the working barrel, a standing valve connected with the working barrel, a rod guide provided with bore portions of different diameters, a means 10 to reciprocate the plunger, said means including a rod having sections of different diameters slidably fitting the respective bore portions of the guide, the rod section of larger diameter having a less cross sectional area 15 than the plunger, and a valved connection between the rod guide and the working barrel communicating with the bore of the working barrel.

7. A pump comprising pump tubing, a 20 working barrel, a valved plunger in the working barrel, a standing valve connected with the working barrel, a rod guide provided with bore portions of different diameters, a means to reciprocate the plunger, said means 25 including a rod having sections of different diameters slidably fitting the respective bore portions of the guide, the rod section of larger diameter having a less cross sectional area than the plunger, said rod having a circumferential groove to catch solid particles entrained in the fluid that may seek to leak between the rod and the inner face of the guide, and a valved connection between the rod guide and the working barrel communicating 35 with the bore of the working barrel.

8. A pump comprising pump tubing, a working barrel, a valved plunger in the working barrel, a standing valve connected with the working barrel, a rod guide provided with 40 bore portions of different diameters, a means to reciprocate the plunger, said means including a rod having sections of different diameters slidably fitting the respective bore portions of the guide, the rod section of larger 45 diameter having a less cross sectional area than the plunger, said rod having a circumferential, helical groove to catch solid particles entrained in the fluid that may seek to leak between the rod and the inner face of 50 the guide, and a valved connection between the rod guide and the working barrel communicating with the bore of the working barrel.

9. A fluid-operated pump comprising a 55 working barrel, a valved plunger in the working barrel, a standing valve connected with the working barrel, a cylinder, a piston in the cylinder, pump tubing, a rod connecting the plunger and piston and provided with portions 60 of different diameters, said rod having a less cross-sectional area than the plunger, a guide provided with bore portions of different diameters closely fitting the respective rod portions, a valved connection below the 65 guide and between the pump tubing and the

working barrel, said valved connection permitting fluid displaced by the larger rod portion on its down stroke to pass from the working barrel into the pump tubing and preventing return of said fluid into the working barrel, and a valve means to admit a power fluid to and exhaust said fluid from the opposite ends of the cylinder to effect reciprocation of the piston.

10. A pump comprising pump tubing, a 70 working barrel, a valved plunger in the working barrel, a standing valve connected with the working barrel, a means to reciprocate the plunger, said means including a rod having portions of different diameters and having a less cross-sectional area than the plunger, a guide provided with bore portions of different diameters respectively fitting the different rod portions, and a valved connection below the guide and between the pump tubing and the working barrel, said valved connection permitting the fluid displaced by said rod on its down stroke to pass from the working barrel into the pump tubing and preventing return of said fluid into the working 80 barrel.

Signed at Los Angeles, California this 14th day of February 1928.
